UNITED STATES PATENT OFFICE.

FRANCIS J. COUTANT; OF NEW YORK, N. Y.

IMPROVEMENT IN FOUNTAIN INKING-PADS FOR HAND-STAMPS.

Specification forming part of Letters Patent No. **146,383**, dated January 13, 1874; application filed October 25, 1873.

To all whom it may concern:

Be it known that I, FRANCIS J. COUTANT, of the city, county, and State of New York, have invented a new and useful Improvement in Fountain Inking-Pads for Hand-Stamps, of which the following is a specification:

The invention will first be fully described, and then pointed out in the claim.

In the accompanying drawing, Figure 1 is a longitudinal vertical section taken on the line *x x* of Fig. 2. Fig. 2 is a top view.

Similar letters of reference indicate corresponding parts.

A is the tank or fountain, which may be made of metal or any material suitable for the purpose. The ink or liquid is introduced into this tank or vessel through the orifice B. C is the pad, which may be made in the usual manner, attached to a plate, D, which rests in a recess in the top of the tank, so as to be readily removed when it is found necessary to renew the ink. E is a ribbon, of any suitable material, the ends of which are attached to and wound tightly around the rollers F and G. These rollers are immersed in the ink, and consequently the ribbon thereon is saturated. H H are finger-wheels on one end of the rollers F G, by means of which the rollers are turned. I I are stuffing-boxes, to prevent leakage. The opposite ends of the rollers run in boxes on the inside of the tank, as seen in the drawings. J J are rollers on the tank, over which the ribbon passes. The ribbon is moved over the pad by turning the rollers F G. The ribbon winds up on one roller and unwinds from the other, and may be moved back and forth, or in either direction, as may be desired. In passing up and down through the top of the tank, a certain amount of friction is required

to keep the ribbon tightly strained across the pad. This is accomplished by means of elastic plates or valves K K, one of which is stationary. The other is gripped between metallic plates, and moved so as to press the valve against the ribbon by means of finger-screws, which move in slots in the top of the tank. Two devices are seen for this purpose, both producing the same result. L is a plate at one end of the tank, through which the screws m m pass, which plate is forced up and the screws moved laterally by the cam-levers N N. The finger-screws O O at the other end are attached to an angle-plate, and produce the same result in a different manner. These elastic valves not only produce the desired friction, but they prevent leakage.

In the ordinary pad for hand-stamps the ink is applied directly to the outside; consequently there is either a surplus or a deficiency the most of the time. In either case, an imperfect impression, a blot, or a faint outline is made, instead of a plain and distinct counterpart of the stamp.

With this fountain-pad the quantity of ink carried up by the ribbon is always the same, and cannot be varied except by compressing the ribbon between the valves.

Having thus described my invention, I claim as new and desire to secure by Letters Patent—

The combination, with ribbon E, of the elastic plates K K, plate L, screws M, and cam-levers N, as and for the purpose specified.

FRANCIS J. COUTANT.
